COMBINED SHELF UNIT, PLURAL UMBRELLA SUPPORT STAND AND HOUSEHOLD ACCESSORY RACK OR SIMILAR ARTICLE

George T. Cockman, Rte. 2, Box 364,
McLeansville, N.C. 27301

Filed Feb. 13, 1974, Ser. No. 442,051

Term of patent 14 years

Int. Cl. D6—04

U.S. Cl. D6—85

FIG. 1

FIG. 3

FIG. 1 is a perspective view of a combined shelf unit, plural umbrella support stand and household accessory rack or similar article showing my new design;

FIG. 2 is a top plan view thereof; and

FIG. 3 is a left end view thereof.

The side not shown in FIG. 1 is like the side shown while the undisclosed end is a mirror image of the end shown in FIG. 3.

I claim:

The ornamental design for a combined shelf unit, plural umbrella support stand and household accessory rack or similar article, as shown and described.
